UNITED STATES PATENT OFFICE.

ALEXANDER A. CANTIN, OF OAKLAND, CALIFORNIA.

DESIGN FOR A PLUMED CAPITAL.

Application filed October 13, 1926. Serial No. 19,314. Term of patent 14 years.

To all whom it may concern:

Be it known that I, ALEXANDER A. CANTIN, a citizen of the United States of America, and a resident of Oakland, county of Alameda, and State of California, have invented a new, original, and ornamental Design for a Plumed Capital, of which the following is a specification, reference being had to the accompanying drawing, forming a part thereof.

The figure in the drawing is a perspective view showing a plumed capital, it being understood that the complete design consists of a pair of plumes, only one of which is shown in the drawing.

I claim:

The ornamental design for a plumed capital substantially as shown.

ALEXANDER A. CANTIN.
